Patented June 16, 1903.

UNITED STATES PATENT OFFICE.

THOMAS MAITLAND CLELAND, OF NEW YORK, N. Y., ASSIGNOR TO AMERICAN TYPE FOUNDERS COMPANY, OF NEW YORK, N. Y., A CORPORATION OF NEW JERSEY.

DESIGN FOR A FONT OF ORNAMENTS.

SPECIFICATION forming part of Design No. 36,368, dated June 16, 1903.

Application filed April 29, 1903. Serial No. 154,897. Term of patent 14 years.

To all whom it may concern:

Be it known that I, THOMAS MAITLAND CLELAND, a citizen of the United States, residing at New York city, county and State of New York, have invented a new, original, and ornamental Design for a Font of Ornaments, of which the following is a specification.

This font comprises ornamental characters, as shown in the accompanying drawing.

What I claim as my invention is— 10

The ornamental design for a font of ornaments as shown.

In testimony whereof I hereunto set my name this 16th day of April, 1903.

THOMAS MAITLAND CLELAND.
